UNITED STATES PATENT OFFICE.

CHARLES W. STURDEVANT, OF SAN FRANCISCO, CALIFORNIA.

METHOD OF CLEANING LOCOMOTIVE BOILERS AND SUPPLYING WATER TO REFILL THE SAME.

Application filed May 5, 1926. Serial No. 106,998.

The invention relates to the cleaning and refilling of locomotive boilers and has as an object the provision of a process of this character which aims to recover so far as possible, without damage to the boiler, the heat units present in the boiler when it arrives in a roundhouse for servicing.

This application is in part a continuation of my application for patent Serial Number 687,989, filed January 23, 1924, for method of supplying water for filling locomotive boilers.

It is a further object of the invention to blow the steam from a locomotive and condense the steam at the same time by the reduction of pressure, and, by the effect of the heat present in the locomotive as it arrives from service, to evaporate a considerable proportion of the water initially liquid in the boiler.

It is a further object of the invention to clean a boiler recovering as much as possible of the water carried off as steam uncontaminated by the sediment in the boiler and to then withdraw the sediment from the boiler without damage to the sheets of the boiler and in the shortest practicable space of time with the requirements in view.

Further objects of the invention will appear from the following description when read in connection with the drawing showing an illustrative embodiment of the apparatus for carrying out the process and wherein the figure is a diagrammatic view of a locomotive, a receiver for collection of the steam and its condensation and connections for carrying out the method.

As shown, a locomotive is indicated at 1 as housed in the usual manner and a receiver or holder for containing the supply of water for locomotives is shown at 2. This receiver is maintained at atmospheric pressure by openings, not shown, which are of such a size and location as to retain the steam discharged into the receiver. To discharge steam into the receiver, an overhead pipe is shown at 3 leading directly into the receiver and which may be common to all of the locomotives which the roundhouse is adapted to receive.

The steam dome, or the highest part of the locomotive boiler is shown at 4. A valve 5 is shown as permanently connected to the steam dome which valve may be connected to the overhead pipe 3 by means

of a pipe fitting 6 through a drop line 7. The end of pipe 7 is shown as provided with a valve 8. To permit of attachment of the locomotive to the discharge pipe even though the locomotive is not spotted exactly the same in every instance, a flexible pipe connection 9 is shown occurring between the valves 5 and 8, a union 10 being provided to connect the flexible connection 9 with the valve 5.

To return water from the receiver to the boiler after the cleaning operation has been completed, a pump 11 is shown connected to the receiver 2 and having its discharge connected through valve 12 and pipe 13 to overhead pipe 14, which latter pipe is also common to all of the locomotives which may be placed in the roundhouse. For connection of pipe 14 to the locomotive, a fitting 15 and a drop pipe 16 are provided, on the end of which latter pipe is located a valve 17.

To withdraw sediment remaining after the steam has been blown down to atmospheric pressure, the water leg of the boiler is fitted in the usual manner with a blow-off valve 18 just above the mud ring of the boiler. Intermediate the valves 17 and 18, a flexible pipe connection is provided at 19, a union 20 being provided to join the connection 19 with the blow-off valve 18. The flexible connection 19 is provided for the same purpose as flexible connection 9, to enable connection to be made with the boiler even though not accurately spotted. Other connections 21 and 22 are provided to connect other locomotives or stalls for the same to the overhead pipes referred to, whereby a number of locomotives can be serviced at the same time. Wash-out plugs located on both sides of the water legs of the boiler just above the mud ring are indicated at 23.

A defect in former provisions for blowing down and cleaning locomotive boilers has been that the steam has been blown off from the bottom of the water legs of the boiler with the end in view of blowing out the sediment in the boiler by means of steam pressure. As a matter of practical operation when this process has been followed it has been necessary to wait from two to three hours after a locomotive is delivered to the roundhouse for the locomotive to cool down in order to avoid damage to the sheets of the fire box and boiler by lowering of the

water therein which exposes the metallic surfaces to the high temperature of the fire box without the protection of a water covering. Other systems wherein the steam has been blown off from the steam dome have injected cold water in the blow-off pipe resulting in the reduction of pressure in the blow-off pipe and a too sudden removal of the steam from the boiler also resulting in damage to the sheets of the boiler. The process provided by the present invention avoids both of these defects by allowing the steam to blow off into a receiver at substantially atmospheric pressure without hastening the blowing off of the steam by reduction of pressure in the blow-off pipe. It is therefore possible by the present process to begin the blowing off of the steam immediately the locomotive is received, the time usually wasted in allowing the locomotive to cool being utilized in blowing down the steam. At the same time the heat present in the fire box as well as the reduction of pressure in the boiler causes a considerable proportion of water initially liquid in the boiler to be evaporated, carried over as steam and condensed in the receiver as distilled water of the highest grade for refilling and also preserving the water in the receiver at the highest practicable temperature for refilling the boiler.

According to the present invention after pressure in the boiler has been reduced to atmospheric, the remaining water in the boiler with the sediment therein is withdrawn through the wash-out plugs 23 or the blow-off valves 18 carrying with it the sediment and scale which is run to waste. The boiler is then washed out through the openings provided by the removal of plugs 23 using the hot water in the receiver tempered by as much cold water as is necessary to reduce the temperature to that at which the wash-out pipe can be handled by the attendants. After the boiler has been washed and plugs 23 replaced, the hot water from the receiver is returned to the boiler by means of pump 11.

It is found by the practice of the present

invention that substantially one-third of the water present in the locomotive when delivered for servicing is recovered as distilled water thus providing a large quantity of water of the finest character for refilling the locomotive boiler, entirely freed of hardness or scale forming elements as well as soluble salts which cause foaming or priming. The process of the present invention has particular value when used in oil fired locomotives which have a large amount of refractory material as linings in their fire boxes, which refractory material under former practice must be allowed to cool down with consequent delay and loss of heat units before the locomotive could be cleaned. It is also found that the locomotive can be placed in service in considerable less time without damage to the sheets of the boiler by the practice of the present invention than by the practice of former methods.

Minor changes may be made in the steps of the process within the scope of the appended claim without departing from its spirit.

I claim:

The method of cleaning a locomotive boiler and supplying water to refill the same comprising discharging the steam from the locomotive initially at substantially working pressure of the locomotive from a point above the water level of the locomotive boiler, into a container at substantially atmospheric pressure without the addition of water to the steam prior to its delivery into said container, with consequent evaporation and discharge as steam of a portion of the water initially liquid in the boiler, discharging sediment and the remaining water from the boiler by gravity at substantially atmospheric pressure and utilizing the stored hot water of condensation at the temperature found in the container in refilling the boiler.

In testimony whereof I affix my signature.

CHARLES W. STURDEVANT.
